Application October 29, 1947, Serial No. 782,733
In Great Britain October 30, 1946

8 Claims. (Cl. 179—27)

1

This invention relates to registering and controlling means and has for its object further improvements in the application of discharge tubes for such purposes.

The main feature of the invention comprises registering and controlling means comprising discharge tubes both for registering numbers and for counting stored numbers.

To make the invention clearly understood, reference will now be made to certain embodiments shown in the accompanying drawings, in which:

Figs. 1A and 1B illustrate an electric counter combined with an electric storage device for use for instance in an automatic telephone system;

Fig. 2 illustrates a code for storing numbers 1 . . . 15 on a set of four storage devices, such as neon tubes;

Fig. 3 illustrates the method of counting out the record on the counter;

Fig. 4 illustrates another embodiment of an electric counter; while

Fig. 5 illustrates another alternative means for triggering one pair of tubes from another.

These figures are also used to illustrate the invention of our copending application, Serial No. 782,734, filed October 29, 1947, now Patent No. 2,576,099.

The arrangement illustrated in Fig. 1 may be used in an automatic telephone system where it is required to select a number by successively operating digit keys, each key corresponding to a digit of the number, to store the number in an electric storing device, and subsequently to send impulses into a line, which correspond to the number selected, or to respond to revertive impulsive from a distant point.

The circuit arrangement of Fig. 1 illustrates a key-sending position at its left hand side, a storage circuit at the lower part of its right hand side, and an electric counter at the upper part of its right hand side.

The key-sending position comprises a sender key SK, ten digit keys corresponding to the numerals 1, 2, . . . 9, 0, a start-send key SSK, a cancel key CK, and a sender busy lamp SBL.

The storage circuit comprises eight sets 1, 2, . . . 7, 8, each of four circuits a, b, c, d, of neon or the like gas discharge tubes Ta, Tb, Tc, Td, each connected in series with a high ohmic resistor Ra, Rb, Rc, Rd respectively. A neon or the like tube needs a potential for striking the tube which is considerably higher than the lowest potential necessary for sustaining the discharge through the tube after the tube has been ignited hereinafter and in the claims shortly called sus-

taining potential). An operating potential between the striking and sustaining potentials will maintain the tube in either of two different stable conditions. If the potential across the tube has been momentarily raised above the striking potential, the tube will ignite and the discharge through the tube will be maintained and the tube be conducting when the potential has returned to the normal operating potential. If the potential is now momentarily lowered below the sustaining potential, the discharge through the tube will be quenched, and the tube will become non-conducting and remain non-conducting when the potential has again returned to the normal operating potential. Thus, each tube may be in one of two different conditions which may be ascertained by sensing the potential across the respective series resistor. As indicated in Fig. 2, a set of four tubes may assume sixteen different patterns depending on which of the four tubes are conducting, and which are non-conducting. By selecting ten different patterns out of the possible sixteen patterns, each digit may be stored and represented on a binary basis on such a set of four tubes. In Fig. 2, each row contains four circles corresponding to the circuits a, b, c, d of a set of four neon tubes each in series with a resistor, the black circles indicating a circuit comprising a conducting tube and the white circles indicating a circuit comprising a non-conducting tube. Fig. 2 illustrates the 16 possible patterns of which ten correspond to the digits 1, 2, . . . 9, 0, these being the only ones used in the example given. Tubes a, b, c, d represent ascending orders of numbers on a binary scale; 1, 2, 4, 8, and record digits in such a way that operating tubes indicate zero and quiescent tubes indicate a binary digit. Thus line 5 from left to right represents the number 0101 on the binary scale or 0+4+0+1 on the decimal scale, while line 9 represents 1001 on the binary scale, or 8+0+0+1 on the decimal scale. It will also be recognised that with the arrangement of Fig. 1 which comprises eight sets each of four neon tubes, a number consisting of up to eight digits may be stored.

For striking the four gas discharge tubes of a set of tubes, triggering capacitors C5, C6, C7, C8 are provided, which are normally charged from a supply source through the resistors R1, R2, R3, R4, to the positive operating potential of the gas discharge tubes. The resistors R1, R2, R3, R4 are shunted respectively by additional capacitors C1, C2, C3, C4. The triggering capacitors are connected in series with resistors R5, R6, R7, R8 for limiting surge currents. In the position illus-

trated in Fig. 1, the triggering capacitors C5, C6, C7, C8 in series with the respective series resistors R5, R6, R7, R8, are connected across various contacts, which will be described further below, to the anodes of the gas discharge tubes Ta, Tb, Tc, Td, of the first set of tubes of the storage circuit.

The electric counter comprises eight cold cathode discharge tubes CT1, CT2, . . . CT7, CT8. Each of these tubes comprises a cold cathode, an anode, and two auxiliary electrodes for striking the tube. The tubes are arranged to form two sets of four tubes, the first set comprising the tubes CT1, CT3, CT5, CT7 and the other set the tubes CT2, CT4, CT6, CT8. The tubes also form four pairs of tubes, the first pair comprising the tubes CT1 and CT2, the second pair the tubes CT3 and CT4, the third the tubes CT5 and CT6, and the fourth the tubes CT7 and CT8.

Before a number is selected, the sender key is closed whereby the relay GA is energised. The contact ga9 of the relay GA is closed for a purpose which will be described further below. The contact ga8 of the relay GA is closed and applies the positive operating potential derived from the supply source to all the anodes of the gas discharge tubes of the storage circuit, the cathodes of the tubes being connected to the respective series resistors, the free terminals of which are connected to the earthed negative operating potential of the supply source. The contact ga3 also applies the positive operating potential to the main anodes of all the cold cathode tubes of the electric counter, the cathodes of the tubes of the first set being connected across the primary windings of cathode transformers T1, T2, T3, T4, and the cathodes of the tubes of the second set being directly connected to the negative terminal of an additional supply source. The contact ga8 is closed and connects a relay CA to the cancel key CK. The contact ga6 connects a relay H to the start send key SSK. The contacts ga5—ga2 connect respectively the triggering capacitors C8, C7, C8, C5 to the digit keys. The contact ga1 connects a relay S to the digit keys.

When now a digit key is operated, a certain combination of gas discharge tubes of the first set of tubes of the storage circuit is ignited in the following manner: Assume the first digit key to be operated is key 5 corresponding to the numeral 5. In this case, as will be seen from Fig. 2, the gas discharge tubes Td and Tb of the first set should be ignited, while the tubes Tc and Ta should not be ignited. By operating the digit key 5, the negative terminal of the additional supply source, whose positive terminal is earthed, is connected to the capacitors C8 and C6. Thereby the charges of these capacitors are reversed. The charging currents flow through the resistors Ra and Rc of the first set of tubes of the storage circuit. Thereby, the potentials across the corresponding tubes Tb and Td are momentarily raised above the striking potential of the tubes Tb and Td which are ignited and remain ignited after the digit key 5 has been released. The capacitors C1, C2, C3, C4 ensure that the ignited tubes are not quenched while the triggering capacitors C6, C8 are recharged on release of the digit key. The operation of a digit key also energises the relay S. Its contact s1 (see right hand bottom corner of Fig. 1) is operated whereby the relay A is energised via back contacts b1—h1, s1 front, ca1, cl2 back. A relay SJ is energised over the closed contact a2 and is locked over its contact s2 to cl3 back. Contact s3 closes the circuit for the sender busy lamp SBL, which

commences glowing. Contact s1 is closed without effect. When the digit key 5 is released, the relay S is de-energised and its contact s1 is released. Thereby, the relay A is locked, right hand winding of B, left hand winding of A, a1 front, s1, ca1, cl2 back. Relay B is energised. The contacts b3—b6 disconnect the triggering capacitors C5, C6, C7, C8 from the first set of gas discharge tubes of the storage circuit and connect them to its second set of gas discharge tubes.

The next operation of a digit key triggers a pattern which represents the numeral corresponding to the respective key on to the second set of gas discharge tubes of the storage circuit in an analogous manner to that just described with reference to the first set of tubes. The relay S is again energised and operation of its contact s1 causes the locked relay A to be released but relay B holds via b1—h1. The release of the digit key causes the relay S to de-energise whereupon the relay C is energised over contacts b2 front, a1, s1 back in series with the locking winding of relay B. Contacts C3, C4, C5, C6 cause the triggering capacitors C5, C6, C7, C8 to be disconnected from the second set of tubes and to be connected to the third set of tubes.

It will be realised that in the manner described patterns corresponding to the digits of a number may successively be impressed on the sets of neon or the like tubes of the storage circuit by successively operating the respective digit keys.

If the number to be stored comprises eight digits, the relay DS is, in a manner similar to the relays B to H, energised on release of the eighth digit key operated and is locked over its contact ds1, while the relay H is released by short-circuit of its left hand winding. If, however, the number to be stored comprises less than eight digits, the start send key SSK has to be operated after the last digit key has been released. Operation of the start send key energises the relay H over the contacts ga6 and ds3, whereby the relay DS is, again, energised and, as before, closes a circuit via a winding of DS, left hand winding of H, contacts h2—s1, ca1, cl2. The main winding of relay H is de-energised by the operation of the contact ds3, while its locking winding is short circuited by contact ds1 which is closed so that relay H releases its contacts. In both cases, the contacts ds4—ds1 disconnect the storage circuit from the triggering capacitors C5, C6, C7, C8. The contact ds8 disconnects the relay S from the digit keys. Operation of DS also closes contact ds9 associated with two additional cold cathode discharge tubes CT9 and CT10, each comprising a cold cathode, a main anode, and an auxiliary anode. The contact ds2 is closed whereby the relay TR is energised via t3 back, ds2 front, h2—s1 back, ca1, cl2 back and locks over tr6, st2, cl2.

The contacts tr1—4 are closed and connect the storage circuit to the electric counter to control the transmission of the stored digits into the line 11 and 12. It will further be appreciated that since the number has been stored in a binary code on the storage circuit, it has to be translated from the binary code into the decimal system when sending corresponding impulses into the line.

A capacitor C16 is normally charged across resistors R9 and R10. The capacitor C16 is connected over surge limiting resistors R11, R12, R13, R14 to the upper auxiliary electrode of each of the cold cathode tubes CT1, CT5, CT3, CT1

forming the first set of cold cathode tubes of the electric counter. The tubes are of the type provided with two auxiliary electrodes either of which may be used for triggering the tube. As explained hereinbefore, the relay GA was energised and its contact *ga3* closed when the sender key was closed. Closing of the contact *ga3* causes the capacitor C16 to be discharged through the resistor R10. Thereby, the potential on the upper auxiliary electrodes of the cold cathode tubes CT1, CT5, CT3, CT1 is momentarily raised, so that these tubes are ignited, the discharge through these tubes being maintained across the main discharge space between the cathodes and anodes, which receive the positive operating potential from the supply source over the closed contact *ga8*, contact *ca3* back and anode resistors R15, R16, R17, R18 respectively. The commencement of the discharge currents across the main discharge spaces of the tubes CT1, CT3, and CT5, which flow through the primary windings of the cathode transformers T1, T2, T3, causes an electromotive force to be momentarily induced in the secondary transformer windings of sufficient amplitude to trigger the cold cathode tubes CT4, CT6, and CT8. These tubes, however, do not sustain since their main anode potential is, at the same time, reduced by currents charging anode capacitors C11, C12, C13. The conditions of the eight tubes of the electric counter is indicated in the rows 1, 2 of Fig. 3, row 2 indicating that the cold cathode tubes CT1, CT3, CT5, CT7 of the first set of tubes are conducting and row 1 indicating that the tubes CT2, CT4, CT6, CT8 are non-conducting. Fig. 3 also indicates that the cold cathode tube CT10 is non-conducting.

The anode capacitors C11, C12, C13 and C10, which is also charged, are connected between the anodes of the four pairs of tubes, one capacitor for each pair. When any of the cold cathode tubes CT2, CT4, CT6, CT8 of the second set of tubes of the electric counter is triggered in a manner to be explained hereafter, the charging current flowing through the respective anode capacitor causes the potential on the anode of the corresponding tube of the first set to be sufficiently lowered, so that such corresponding tube is quenched. In other words, the provision of the anode capacitors ensures that on triggering and striking of one tube (no matter whether it belongs to the first or second set of four tubes) of the electric counter, the other tube belonging to the same pair of tubes is automatically quenched.

Closing of the contacts *tr1*—*tr4* connects the cathodes of the neon or the like discharge tubes *Ta*, *Tb*, *Tc*, *Td* of the first set of tubes of the storage circuit respectively to limiting resistors R22, R23, R24, R25 connected to the lower auxiliary electrodes of the cold cathode tubes CT8, CT6, CT4, CT2 of the electric counter. Any ionised storage tube causes a potential drop across its series resistor which is applied to the said auxiliary electrode of the corresponding cold cathode tube of the second set of the electric counter and causes such tube to strike. Thereby the other tube of the same pair of tubes is quenched.

In the example discussed hereinbefore in which the first digit key operated was the digit key 5, the binary code corresponding to the numeral 5 was impressed on the first set of gas discharge tubes of the storage circuit. Consequently the tubes *Tb* and *Td* of the first set of tubes of the storage circuit are ignited and the tubes *Ta* and

Tc are not ignited. This causes a voltage drop across the resistors *Rb* and *Rd* of the first set which, in turn, causes the cold cathode tubes CT8 and CT4 of the second set of tubes of the electric counter to strike when the contacts *tr1*—*tr4* are closed. The tubes CT8 and CT4 belong to the fourth and second pairs of tubes of the electric counter. These tubes remain ionised and striking of these tubes causes the other tubes of the fourth and second pairs, namely tubes CT7 and CT3, to be quenched as described above. The condition of the eight tubes of the electric counter after the operation of the relay TR is represented in the third and fourth rows of Fig. 3. The pattern corresponding to the digit 5, which is repeated in the last row of Fig. 2 is thus transferred to the second set of tubes of the electric counter (as shown in the third row from the bottom of Fig. 3); the first set of tubes of the electric counter represents a pattern (see fourth row of Fig. 3) that is complementary to that impressed on the said second set of tubes, the tube CT10 being still non-conducting. The cold cathode tubes contrary to the arrangement of the neons work on the basis that an operated tube represents a binary digit while an unoperated tube represents a zero. The tubes CT1—7 therefore record the number stored while the tubes CT2—8 record the complement to fifteen.

From an inspection of Fig. 2 it will be seen that the digit code has been chosen in such a manner that any digit requires either tube *Tc* or tube *Td* or both these tubes of a set of the storage circuit to be ignited. Consequently, when the pattern has been transferred to the electric counter either tube CT8 or tube CT6 or both these tubes of the second set of tubes will be ionised. Ionisation of either or both these tubes causes a negative pulse, owing to the sudden change of potential, on the corresponding anode or anodes of the tube or tubes CT8 and/or CT6 which triggers across the capacitor C15 and resistor R37 and/or capacitor C14 and resistor R36, the cold cathode tube CT9 which becomes ionised across the discharge space between its cold cathode and anode. Thereby the relay ST is energised. Its contact *st1* is opened; contact *st2* is opened and de-energises relay TR whereby the cold cathode tubes of the second set of the electric counter are disconnected from the gas discharge tubes of the first set of the storage circuit; contact *st3* is closed and prepares the anode circuit of a cold cathode tube CT11; contact *st4* energises the relay S; contact *st5* is closed and connects the auxiliary electrode of the cold cathode tube CT10 to the secondary winding of the cathode transformer T4 of the tube CT7; contact *st6* is closed.

An impulse sender Z is connected to the line *l1*, *l2*, and comprises contact springs *Zl* connected across the line *l1*, *l2*, which are periodically opened and closed so that impulses may be sent into the line *l1*, *l2* while the contact springs *Zl* are open. Additional contact springs *Zs* are provided which operate in synchronism with the springs *Zl*. While the springs *Zs* are closed a relay IG is short-circuited. Now, owing to the contacts *tr5* and *st6* being closed the relay IG is energised on the next opening of the contact springs *Zs*. Its contact *ig1* disconnects the springs *Zs* from the relay IG which, thus, will no longer be short-circuited when the springs *Zs* close again, and connects the said springs to the relay I which will be energised on closing of the springs *Zs*. Contact *ig3* is closed (see right hand end of counter) and discharges a triggering

capacitor C9 across a resistor R33, the capacitor C9 being normally charged from the additional supply source across the resistors R38 and R39. The capacitor C8 is connected across limiting resistors R30 and R34 to the interconnected auxiliary electrodes of the cold cathode tubes CT1, CT2 which form the first pair of tubes of the electric counter. By the discharge of the capacitor C9 on closing of the contact i_3 the non-ignited tube of the first pair is ignited. This in turn causes the previously ignited tube to be quenched as hereinbefore described. In the example referred to above, the tube CT2 was not ignited and the tube CT1 ignited. After operation of the relay IG and closing of the contact i_3 the tube CT2 is ignited and the tube CT1 is not ignited. The condition of the eight tubes of the electric counter after the operation of the relay IG is represented in the 5th and 6th rows of Fig. 3, the tube CT10 being still non-conducting. The condition of the upper set of tubes now corresponds to digit 4, Fig. 2. It will be seen that an impulse has been interpolated prior to synchronous impulsion both to line l_1, l_2 and to the counting tubes. This is because it is desired not only to count out the digit to the condition shown in rows 13, 14, Fig. 3, but to return these tubes to the original condition shown both in rows 1, 2 and rows 15, 16, Fig. 3.

When the springs Zs close again, the relay I is energised and causes the contact i_1 to open. Thereby, the triggering capacitor C9 is recharged.

Contacts i_2 remove the short-circuit from springs Zl but not in time for an impulse to be sent to line during the opening of springs Zs, Zl which causes operation of IG. When the springs Zs open again, the springs Zl also open allowing the impulse sender to send a first impulse into the line l_1, l_2 , which is no longer short-circuited by the contact i_2 . On opening of the springs Zs, the relay I is de-energised, whereby the contact i_1 is closed again and the capacitor C9 discharged, the contact i_3 being closed. The release of the relay I thus causes, in the example assumed, the tube CT1 to be ignited and the tube CT2 to be quenched. Striking of the tube CT1 causes an impulse through the secondary winding of the cathode transformer T1 which is connected across resistors R29 and R33 to the auxiliary electrodes of the second pair of tubes CT3 and CT4. Thereby the tube CT3 is now ignited and the tube CT4 is quenched. As the tube CT3 belongs to the first set of tubes, striking of tube CT3 causes a pulse through the secondary winding of its cathode transformer T2 which is connected across resistors R28 and R32 to the auxiliary electrodes of the third pair of tubes CT5 and CT6. Thereby, in the example assumed, the tube CT5 of the first set is quenched and the tube CT6 ignited. Since the ignited tube CT6 of the third pair is not associated with a cathode transformer, the tubes of the fourth pair are not triggered, the condition of the counter being indicated by the 7th and 8th rows from the bottom of Fig. 3, the tube 10 being still not ignited. This further impulse to the counter has altered the setting of the second set of tubes from digit 4 to digit 3. When the springs Zs close again the relay I is energised, contact i_1 is opened, the triggering capacitor C9 is charged, and on opening of the springs Zs the relay I is released for the second time. A second impulse is sent into the line l_1, l_2 owing to the simultaneous opening of the springs Zl. Again, the capacitor C9 is discharged, whereby the tube

CT2 of the second set is ignited and the tube CT1 of the first set is quenched. Since the ignited tube belongs to the second set no further tube is affected, the condition of the electric counter being now represented by the 9th and 10th rows of Fig. 3, corresponding to digit 2. The springs Zl and Zs continue to operate in the manner described, whereby the relay I continues to be alternately energised and de-energised. On each release of the relay I an impulse is sent into the line l_1, l_2 and the first group of cold cathode tubes of the electric counter is triggered whereby the pattern on the electric counter is changed in the manner just described, the pattern after the 15th release of the relay I being shown in the 11th and 12th rows of Fig. 3, that after the fourth release in the 13th and 14th rows and that after the fifth release in the 15th and 16th rows of Fig. 3. It will be seen that after the fifth release all the cold cathode tubes of the first set are ignited and those of the second set quenched. Tube CT10 is also ignited as will be described below. The digit code shown in Fig. 2 has been so chosen that if any numeral, say for example numeral 5 or 8, has been stored, the condition of the tubes of the electric counter indicated in rows 15, 16, Fig. 3, will be reached after a corresponding number in the example 5 or 8, of releases of the relay I, and after a corresponding number of impulses, one on each release of this relay, has been sent into the line l_1, l_2 . Furthermore, it will be recognised that whichever of the patterns of Fig. 2 is impressed on the record set of cold cathode tubes from the storage circuit, CT1 will be quenched either immediately if the pattern is that of digit 1-7 or after one or more pulses to the counting set, and is only re-ignited when the condition shown in the top row of Fig. 3 has been reached.

Re-igniting of the tube CT1 causes an impulse 40 to be sent through the secondary winding of the cathode transformer T4, whereby the cold cathode tube CT10 is ignited, the contact s_5 being closed. Thereby the relay T is energised. Its contact t_1 quenches the tube CT9 and completes 45 the anode circuit for tube CT11; contact t_2 short-circuits the line l_1, l_2 , and prevents further impulses from reaching the line; contact t_3 changes over; contact t_4 disconnects the relays I and IG from battery. Quenching of the tube CT9 causes 50 the relay ST to be de-energised. Thereby, the relay S is de-energised whereby the contact s_1 returns to normal. When ST operates S, the change-over of contacts s operated relay A as previously described. Release of S now energises 55 B in series with A and connects second set of storage tubes to contacts t_1-4 so that when eventually relay TR is re-energised, this second set of tubes will be connected to the electric counter. Contact t_1 also causes a capacitor C18 60 to be charged through a resistor R49 via s_1, t_1, d_9, R_26 , positive battery, the time needed for charging the capacitor C18 providing a time interval between successive groups of impulses sent into the line and corresponding successive digits. 65 When the capacitor C18 has been charged, the cold cathode tube CT11 ignites and discharges via the charging circuit of C18. Relay ID is energised. Contact i_1 is closed and causes the capacitor C18 to discharge; contact i_2 switches over, whereby the cold cathode tube CT10 is quenched and a positive potential applied to the main anode of the cold cathode tube CT9. Contact i_3 is closed and energises the relay TR via s_2, c_2 back. Thereby the contacts t_1-4 are 75 closed and the electric counter is connected to

the second set of tubes of the storage circuit and is ready to receive, therefrom, the pattern previously impressed thereon and corresponding to the second digit of the stored number. The counter, again, operates as before.

If eight digits have been stored the release of the relay H, after the eighth digit has been counted and transmitted into the line, causes a clear down relay CL to be energised over the contacts t_3 , ds_2 , h_2 to b_2 , a_1 , s_1 , ca_1 , cl_2 . Contact cl_1 locks the relay CL across contact s_1 which is closed, relay SJ having been operated on the first operating of relay A and having remained locked thereafter via s_2 , cl_3 to light the sender busy lamp SBL. Contacts cl_2 and cl_3 are opened and release all the relays. The release of the relay SJ opens contact s_1 , whereby the clear down relay CL itself is released, while contact s_3 opens and extinguishes the sender busy lamp.

If less than eight digits have been stored, the arrangement clears down when no code is transferred from a set of tubes of the storage circuit to the electric counter, since if no code is present neither of the cold cathode tubes CT8 and CT6 will be ignited. Therefore, the cold cathode tube CT9 is not triggered and relay ST is not energised. The clear down relay CL, which is slow to operate, will now be energised across contacts s_1 , tr_1 , which are both closed, and contact s_1 back. Operation of the relay CL clears down the arrangement in the manner just described.

If an incorrect digit has been keyed, the cancel key CK may be operated to restore the storage circuit to its initial condition. On operation of the cancel key relay CA is energised. Contact ca_3 is opened, whereby the potential across all the neon or the like tubes of the storage circuit is lowered below the sustaining potential and all the tubes which may be ignited are quenched. Contact ca_1 is opened and de-energises any of the relays A . . . H which may be energised. When the cancel key has been released, the relay CA is de-energised and the circuit is in its initial condition ready for operation.

It will be realised it would be possible to replace the combination of set of storage neons and the common counting tube assembly by a series of counting tube assemblies each directly marked from the keys or by other marking means.

Modifications of the arrangement illustrated in Fig. 1 are possible. For example, in the electric counter the cathode transformers T1, T2, T3, T4 may be replaced by capacitors combined with a rectifier, for example, a dry rectifier, or by neon tubes on the lines described later.

A circuit diagram of such a modified electric counter is shown in Fig. 4, which will now be described. The arrangement of Fig. 4 comprises eight cold cathode tubes CTO1, CTO3, CTO5, CTO7 forming the first set of tubes, and CTO2, CTO4, CTO6, CTO8 forming the second set of tubes. Each tube has a cold cathode connected across a resistor RO1, RO3, RO5, RO7; RO2, RO4, RO6, RO8 respectively to the negative potential of the additional supply source, the positive terminal of which is earthed. The anode of each tube has, in operation, applied to it the positive operating potential derived from the main supply source (not shown) whose negative terminal is earthed. Each tube has two auxiliary electrodes for triggering the tubes. One auxiliary electrode of each tube of the second set is connected across a resistor RO36, RO35, RO34, RO33 respectively to terminals TO1, TO2, TO3, TO4 for triggering

some of these tubes and thereby impressing a digit code on the tubes of the first set. The other auxiliary electrode of each tube of the second set is connected across two resistors RO10, RO9; RO12, RO11; RO14, RO13; RO16, RO15, respectively to an auxiliary electrode of the corresponding tube of the first set. The other auxiliary electrode of each tube of the first set is connected across a resistor RO21, RO22, RO23, RO24, respectively to a triggering capacitor CO9 charged from the additional supply source across resistors RO25, RO26. The cold cathodes of the tubes of each pair are connected together across capacitors CO1, CO2, CO3, CO4 respectively. A further triggering capacitor CO10 is connected to the resistors RO9, RO10, and is charged from the additional supply source across resistors RO17, and RO27. The cold cathode of each tube of the second set is connected to one terminal of a rectifier MRA, MRB, MRC, MRD respectively, the other terminal of which is respectively connected to an electrode of a capacitor CO5, CO6, CO7, CO8, the other electrode of which is respectively connected to a resistor RO18, RO19, RO20, RO32, the free ends of which are earthed. The said other electrode of each of the capacitors CO5, CO6, CO7, CO8 is also connected respectively to the pair of resistors RO11, RO12; RO13, RO14; RO15, RO16, while the said other electrode of capacitor CO8 is connected to a terminal TO5. The capacitors CO5, CO6, CO7, CO8 are connected to the positive terminal of an auxiliary supply source whose negative terminal is earthed, and are charged respectively over the pairs of resistors RO28, RO18; RO29, RO19; RO30, RO20; RO31, RO32. A start relay STO is connected between the additional supply source and a terminal TO6 and an impulse relay IPO is connected between the additional supply source and a terminal TO7.

The operation of the arrangement is as follows: The start relay STO is energised by applying earth potential to its terminal TO6. The contact sto_1 is closed and discharges the triggering capacitor CO9 across the resistor RO25. Thereby the cold discharge tubes of the first set are triggered and ignite across the surge limiting resistors RO21, RO22, RO23, RO24 respectively. The counter is capable of counting a total of sixteen impulses and is operated by earth impulses applied to terminal TO1. Each such impulse energises the impulse relay IPO. The contact ipo_1 is closed and causes the triggering capacitor CO10 to be discharged through the resistor RO17. The potential drop caused thereby is applied across the current limiting resistors RO9, RO10 to the auxiliary anodes of the tubes CTO1, CTO2 of the first pair of tubes. Tube CTO1 is already conducting. Tube CTO2 is triggered and ignites. Owing to the voltage drop across the resistor RO2, the potential of the cold cathode of tube CTO2 rises from its original negative potential to a positive potential, which equals the difference between the positive potential applied to the anode and the drop of potential across the main discharge gap. This rise in potential discharges the cathode coupling capacitor CO1, which causes the cathode potential of the tube CTO1 to increase positively and to reduce the potential across the main discharge gap of the tube CTO1 which is therefore de-ionised and ceases to conduct. Thus, tube CTO1 is now quenched and tube CTO2 ignited. More generally, whenever a tube ignites the other, previously ignited, tube of the same group is quenched owing to the flow of

a discharge current from the respective capacitor CO1, CO2, CO3, CO4. Quenching of the tube CTO1 and igniting of the tube CTO2 which belongs to the second set does not affect the tubes CTO3 and CTO4 of the next succeeding group since the cathode potential of the tube CTO2 does not rise above the positive bias potential applied to the biasing resistor RO28 and the rectifier MRA presents a high resistance to the flow of current in the direction from the resistor RO28 to the cathode of tube CTO2. When the relay IPO is de-energised, its contact *ipol* is released and the triggering capacitor CO10 is charged again.

The second operation of the impulse relay IPO, again, closes the contact *ipol*, whereby the triggering capacitor CO10 is, again, discharged. Thereby, the tube CTO1 of the first group is now ignited and the tube CTO2 of the first group quenched in a manner analogous to that just described. However, when a tube, such as tube CTO1, of the first set of tubes ignites, a triggering impulse is transmitted to the next succeeding group, so as to ignite that tube which was previously not ignited and to quench the other tube. If the tube now ignited belongs to the first set, a triggering impulse is, again, transmitted to the following group, and so on. This effect will now be explained with reference to the first group of tubes. A similar effect takes place whenever a tube of the first set and belonging to any other group ignites. When tube CTO1 ignites, the discharge current from the capacitor CO1 momentarily raises the potential on the cathode of the tube CTO2 sufficiently to quench the tube CTO2. The cathode potential of the tube CTO2 is momentarily higher than the positive biasing voltage across the resistor RO28. Therefore, a current flows from the cathode of the tube CTO2 across the rectifier MRA to the resistor RO28 and causes a positive triggering impulse to be transmitted across the capacitor CO5 to the resistors RO11, RO12. This impulse causes the tube CTO4 to ignite whereupon the tube CTO3 is quenched.

In an analogous manner successive operations of the impulse relay IPO and its contact *ipol* cause the tubes CTO1 and CTO2 alternately to be ignited and quenched. As explained above, whenever a tube of the first set ignites, a triggering impulse is transmitted to the next succeeding group of tubes. On the sixteenth operation of the impulse relay IPO and its contact *ipol*, tube CTO1 is ignited and tube CTO8 is quenched. Igniting of the tube CTO1, which belongs to the first set, causes a positive triggering impulse to be sent across the capacitor CO8 to the terminal TO5, which impulse may be employed to operate an auxiliary circuit (not shown) thereby to indicate that the counter has counted sixteen impulses and is ready to receive a further set of sixteen impulses.

If the electric counter is required to count less than sixteen impulses, it may be pre-set by impressing a suitable pattern of positive potentials to terminals TO1, TO2, TO3, TO4, causing the corresponding tubes of the second set to be triggered and to ignite. For example, if the counter is used in an arrangement similar to that of Fig. 1, the terminals TO1, TO2, TO3, TO4 should be connected to the counter side of the contacts *tr1*—4 respectively of Fig. 1, the contact TO5 being connected to the auxiliary anode of tube CT10 of Fig. 1, triggering connections similar to those shown in Fig. 1 being provided from the tubes CTO8, CTO6, of Fig. 3 to tube CT9 and contact

5 of Fig. 1, and the relays STO and IPO of Fig. 3 being respectively replaced by the relays GA and I of Fig. 1. Conversely, with obvious modifications, the electric counter of Fig. 1 may be used independently from the remainder of Fig. 1 for counting sixteen impulses, or less impulses if suitably pre-set.

In Fig. 5, which shows the last two pairs of tubes of a counting set, a small neon tube, e. g. N3, N4 replaces the rectifier network shown in Fig. 4. This arrangement has the advantage of simplicity, but may not be so flexible as the rectifier network. The potential changes are the same as before. The positive peak potential which occurs when CT6 is de-ionised is used to trigger the next pair of tubes. Since the level of potential across R2 is too high, a neon N3 is arranged in series such that the potential drop across the discharge gap of the tube reduces the potential applied to the control electrodes of the next pair to the required value.

It will be appreciated that it would be possible to insert a cross-connection frame between the storage sets of Fig. 1 and the counting sets so that 25 translated digits are sent out.

What is claimed is:

1. A system for the electrical storage of information comprising a plurality of storage elements grouped according to code requirements, a plurality of digit key switching means, means responsive to the operation of said key switching means for selectively electrically connecting a group of said storage elements to said switching means, and a plurality of direct-current operated triggering means, common to all said groups of said storage elements and included in said electrical connecting means, each of said storage elements being operatively responsive to the operation of a separate one of said triggering means, when connected to said triggering means by said connecting means, said triggering means being selectively operatively responsive in combinations to the operation of each digit key switching means, whereby each digit key switching means, when operated selectively operates a combination of said triggering means and thus operates a predetermined combination of the connected group of said storage elements corresponding to the digital value of said digit key switching means on a codal basis.

2. A registering and controlling system for automatic telephony comprising a plurality of electron discharge devices arranged in groups according to codal requirements, each of said discharge devices being capable of assuming either of two conditions of stability, a plurality of direct current operated triggering means common to all said groups of discharge devices, means for selectively connecting all of said triggering means individually to a group of said devices, and digit key switching means selectively electrically connected to said triggering means for controlling said connecting means and for operating predetermined combinations of said triggering means, means for normally maintaining said discharge devices in one condition of stability, each of said discharge devices being responsive to the operation of a triggering device connected to it for shifting to its other condition of stability, whereby the operation of one of said key switching means will operate a predetermined combination of triggering means which in turn will shift a corresponding combination of a group of said discharge devices from one condition of stability to the other.

3. A system for the electrical storage of information comprising a plurality of electron discharge devices arranged in groups according to codal requirements, a plurality of triggering means common to all of said groups comprising a plurality of direct-current operated triggering elements corresponding to the number of discharge devices in a group, means for electrically connecting said triggering devices to a group of said devices with said triggering elements respectively connected to the devices of said group, a plurality of digit keys connected to said triggering means, each digit key operative to control predetermined combinations of said triggering elements, and stepping means responsive to the sequential operation of said digit keys and included in electrical connection between said triggering means and said discharge devices for controlling said connecting means to connect said triggering means sequentially to said groups of discharge devices.

4. A system for the electrical storage of information comprising a plurality of electron discharge devices grouped according to codal requirements, a plurality of triggering means electrically connected to said discharge devices and comprising a triggering element for each of said discharge devices of a group, said triggering elements being common to all said groups, and a plurality of digit keys connected to said triggering means and operative to control predetermined combinations of said triggering elements, stepping means sequentially responsive to said digit keys included in said electrical connection between said triggering means and said discharge devices for stepping said common triggering means to an untriggered group of said discharge devices, said stepping means comprising a plurality of first electromagnetic relays, one relay corresponding to each group of discharge devices, said relays being serially connected to each other, a source of potential connected to each of said relays, a second electromagnetic relay, circuit means connecting said second relay to said digit keys and said source of potential so that depression of said digit keys is operable to energize said relay and release of said digit keys is operable to de-energize said relay, signal contact means responsive to said second relay included in the series circuit of said plurality of first relays, plural contacts associated with said plurality of first relays and operable sequentially to step the operation of said digit keys, additional contacts controlled by each of said plurality of first relays included in said electrical connections between said common triggering means and said discharge devices whereby successive operation of said digit keys sequentially energizes relays to step the connections of said common triggering means to successive groups of discharge devices.

5. A registering and controlling system for automatic telephony comprising a plurality of gas filled discharge devices grouped according to codal requirements, each of said discharge devices having two electrodes and capable of assuming two conditions of stability depending on the voltage applied across said electrodes, an initiating switch, a first source of potential, an electromagnetic relay serially connected between said initiating switch and said source of potential, a first contact responsive to said relay for applying said source of potential to common electrodes of said discharge devices, a plurality of resistors each serially connected to another electrode of

said discharge devices and to a common junction, said discharge devices being maintained in one of the conditions of stability by said source of potential, a plurality of digit keys, a second source of potential connected to said digit keys, second contacts responsive to said relay for connecting said digit keys to a first group of said discharge devices, plural triggering means included in said connections between said digit keys and said discharge devices, said triggering means corresponding in number to said discharge devices of a group and being common to all such groups, wherein said triggering means comprises a plurality of capacitors, one corresponding to each discharge device of a group, a plurality of resistors serially connected respectively to said capacitors and said first source of potential for maintaining a charge on said capacitors, said digit keys being operable to connect said second source of potential to predetermined combinations of said capacitors for reversing the charge on said capacitors, whereby said charging currents flow through said resistor means serially connected to said second electrodes of the discharge devices thereby raising the potential on those discharge devices corresponding to the capacitors of the predetermined selection to change their condition of stability.

6. A registering and controlling system for automatic telephony as claimed in claim 5, wherein each of said plural triggering means is connected in series with an additional resistor for limiting the surge current on charging and discharging said triggering capacitors, and each of said triggering means is connected in parallel with an additional capacitor to prevent said triggered discharge devices of a group from being quenched when said triggering capacitors are recharged on release of said digit keys.

7. A register sender for automatic telephone systems comprising a plurality of discharge devices grouped according to code requirements on a binary basis, said devices being capable of assuming two conditions of stability, a set of keys, means electrically connecting said discharge devices to said keys, means operative upon the actuation of a key of said set to operate predetermined combinations of said discharge devices of a group to register in binary code form a number representative of the digital value of said key, and additional means actuated by said key set upon release of a key for stepping the connections of said last named means to a different group of said discharge devices.

8. A register controller comprising a plurality of electric storage devices, each comprising members adapted to assume one or the other of two conditions of stability for storing each digit of a number in a separate device in a pattern corresponding to a binary code for the digit, means normally maintaining said members in one condition of stability, a plurality of triggering means, each of said members of said storage devices being adapted to shift to its other condition of stability when a triggering means connected to it is operated, a plurality of digit key switches, circuit means electrically connecting each of said digit key switches to a different combination of said triggering means, each of said triggering means being adapted to operate when a digit key switch connected to it is operated, stepping means comprising relays actuated by the operation of said digit key switches, contacts operatively associated with each of said relays, electrical connecting means including said contacts for con-

necting said triggering means respectively to the members of successive of said electric storage devices when said relays are successively operated, and means for operating said relays in succession by successive operation of said digit key switches, whereby successive operation of said digit key switches operates selective members of said storage devices, said devices being sequentially connected to said triggering means by operation of said relays.
